BOOT HANGER

Noel Van Tilburg, Minneapolis, Minn.

Application August 31, 1945, Serial No. 613,881

1 Claim. (Cl. 211—35)

1 My invention provides an extremely simple, low-cost and highly efficient boot hanger, the word "boot" being used in a liberal sense to include what is sometimes called "shoes," but is particularly designed as a convenient and efficient device for hanging boots, such as hunters' and lumberman's boots and rubber boots in position for drying and if exceedingly wet, for draining. The improved device, as preferably designed, is of wire construction throughout and comprises normally vertical and horizontal sections which may be folded into a flat position against a wall or the like when not in use, or for shipment and storage.

The invention in its preferred form is illustrated in the accompanying drawing wherein like characters indicate like parts throughout the several views:

Referring to the drawing:

Fig. 1 is a side elevation of my novel device, the dotted line position indicating the folded position thereof; and

Fig. 2 is a perspective view.

The device consists of a normally vertical frame section 1 which is, preferably and as shown, rectangular in shape and made up of laterally spaced substantially parallel upper and lower legs or members 2 and 3, respectively, end members 4 and 5, and an intermediate member 6, having its extremities connected to end members 4 and 5 and being substantially parallel to the upper and lower legs or members 2 and 3. The primary function of the lower leg member 3 is to add stability and rigidity to the normally vertical frame member 1 and in practice this leg 3 could be omitted, thereby leaving only the rectangular frame consisting of the upper and lower substantially parallel legs 2 and 6 and side legs or members 4 and 5.

Frame member 1 is adapted to be secured to a wall, or the like A, and for this purpose I preferably provide a reinforcing strut 7 which connects the upper and lower legs or members 2 and 3 substantially at their medial portions and has its upper and lower ends bent to form outwardly projecting U-shaped anchoring eyes 8 and 9, through which head screws 9a or the like are adapted to pass.

Cooperating with frame section 1 is a normally horizontal frame section 10 preferably formed of a single piece of wire and comprising laterally spaced guide arms 11 and 12, having a pair of laterally spaced boot receiving apertures in the form of forks 13 and 14 therebetween. The inner ends of guide arms 11 and 12 are bent to

5 form loops at 15 and 16 which loosely encompass the intermediate leg 6 of normally vertical frame 1, whereby to provide pivots. A pair of laterally spaced diagonal supporting arms 17 and 18 have their upper ends loosely looped over upper leg member 2 of normally vertical frame section 1 at 19 and 20, respectively, to permit pivotal movements thereof on a horizontal axis. The lower ends of supporting arms 17 and 18 are 10 loosely looped at 21 and 22, respectively, around the guide arms 11 and 12 and are slidable thereon.

It will be observed that fork 13 is made up of laterally spaced tines 23 and 24. Likewise, fork 15 14 is made up of laterally spaced tines 25 and 26. A reinforcing strut 27 is rigidly connected to guide arm 11 and tine 23 of fork 13. Likewise, a reinforcing strut 28 is rigidly connected to guide arm 12 and tine 26 of fork 14. Reinforcing struts 27 and 28 are so spaced on guide arms 11 and 12, respectively, so as to provide stops for the sliding looped ends 21 and 22 of supporting arms 17 and 18, thus preventing frame section 10 from dropping further after it has 20 reached an approximately horizontal position.

For the purpose of providing greater stability and reinforcement to the outwardly extended inner tines 24 and 25 of forks 13 and 14, I provide a normally horizontal reinforcing arm 29 30 having its inner end pivoted at 30 to the approximate center of intermediate leg 6 of normally vertical frame section 1 in alignment with the pivotal connections of guide arms 11 and 12 therewith, and having its outer end extending 35 outwardly between said tines 24 and 25. Laterally spaced cross members 31 and 32 have their ends rigidly connected to tines 24 and 25 and have their centers rigidly connected to reinforcing arm 29.

40 From the above it will be obvious that when my novel boot hanger is connected to a wall or other supporting structure, as illustrated in Fig. 1, the normally horizontal frame section 10 will, under the action of gravity, fall to the position indicated by full lines, where its downward motion will be checked by the looped lower ends 21 and 22 of supporting arms 17 and 18 abutting against the transverse reinforcing struts 27 and 28. However, if it is desired to collapse the structure or fold the same against the wall, it is only necessary to push upward on the outer end of the normally horizontal frame section 10, so that the looped ends 15 and 16 of guide arms 11 and 12 pivot on intermediate leg 6 of frame section 1. Simultaneously, the looped ends 21 and

22 of supporting arms 17 and 18 will slide outwardly and upwardly on guide arms 11 and 12 until the structure reaches the position as indicated by dotted lines in Fig. 1. The structure may be so arranged that when in this position there is adequate frictional engagement between the guide arms 11 and 12 and the looped ends 21 and 22 of supporting arms 17 and 18 to retain it in its folded position.

If desired, an elongated metal plate or the like, such as indicated at B, and which may be used for advertising or the like, may be secured to the spaced side legs 4 and 5 of the normally vertical frame section, at but slight additional cost and without in any manner interfering with the action of the boot hanger.

In practice, it is desirable to insert a boot or the like, such as indicated at C, heel first into the U-shaped boot receiving forks 13 and 14. The spread of each of said forks is such as it will engage the inverted boots with considerable friction just below the soles and thereby hold the boots firmly in the best kind of position for drying and maintaining good form.

While I have described a commercial form of my invention it should be obvious that the same is subject to slight changes and modifications without departing from the spirit of the invention, as defined in the appended claim.

What I claim is:

In a device of the class described, a normally vertical frame section having spaced upper, intermediate, and lower members, and spaced end legs, and adapted to be secured to a wall, a normally horizontal frame section horizontally pivoted to the intermediate member of said normally vertical frame section, said normally horizontal frame section comprising laterally spaced guide arms projecting outwardly from the pivot axis and being provided between said guide arms with a pair of outwardly opening boot receiving forks, a pair of diagonal supporting arms, each pivoted at one end to the upper member 10 of said normally vertical frame section and at its 15 other end loosely embracing and being slidable on the guide arms of the normally horizontal frame whereby to permit the normally vertical and normally horizontal sections to be collapsed in side-by-side relationship, stop means on said 20 guide arms preventing downward movement of said normally horizontal frame section beyond a substantially horizontal position, and a reinforcing arm pivoted at its rear end to the medial portion of the intermediate member of the normally vertical frame section and rigidly connected at its front end to the outwardly projecting end portions of said boot receiving forks.

NOEL VAN TILBURG.
